ANTIVIBRATION OR SHOCK ABSORBER MOUNT

Dwight L. Lane, Dayton, Ohio

Application June 7, 1944, Serial No. 539,169

6 Claims. (Cl. 248-22)

(Granted under the act of March 3, 1883, as amended April 30, 1928; 370 O. G. 757)

The invention described herein may be manufactured and used by or for the Government for governmental purposes, without the payment to me of any royalty thereon.

The invention to be hereinafter described relates to anti-vibration or shock-absorber mounts.

It has been common practice to use various constructions and materials to take up, dampen or absorb shocks, jolts and vibrations in many types of machines and vehicles. Springs, rubber, air cushions and liquid columns are among the means used in various arrangements and dispositions. The particular machine or equipment in which they are used is an important factor in determining which material shall be chosen and how it shall be arranged or disposed.

In order to more clearly disclose the construction, arrangement and disposition of the invention reference should be had to the accompanying drawing forming part of the present application.

Throughout the several figures of the drawing like reference characters designate the same parts in the several views.

In the drawing—

Fig. 1 is a side elevation, assembled;

Fig. 2 is a side elevation partly broken away to show details; and

Fig. 3 is an end view of Fig. 1.

Referring to the drawing in detail, 1 indicates the cradle of usual form, adapted to receive and support a dynamotor or other machine subject to considerable vibration. This cradle is provided with footings 2 at opposite ends and opposite sides. To these footings are secured in any usual and well known manner yielding compression shock or vibration elements or members 3 of synthetic rubber, rubber or like material. The machine shown is cylindrical. The cradle 1 shaped to approximately fit and receive the under surface of the machine rises at the sides, appreciably, above the ends. The side footings are, accordingly correspondingly above the end footings. That, in turn, places the side members 3 above the end members. To seat those side members in operative position, plates 4 are provided, secured to and extending upwardly from the cover 5 of the base 6. In the instance shown, the base is a case or box containing the various conductors and binding posts. The top of this case is provided with an opening 1' about which extends an upwardly and inwardly extending or frusto-conical flange 7 through which the wiring passes from the base 6 to the dynamotor. A tubular guide 8 carried by the under side of the

cradle leads the wires from the base 6 to the inlet to the interior of the dynamotor. Guide 8 is constructed and disposed to cooperate with flange 7 through an interposed shock and vibration dampening member. To that end, it has an outwardly rolled curved flange 9 extending about its free end. This flange is approximately complementary to flange 7. In assembled position, as in Fig. 2, the guide 8 and flanges 7 and 9 are so spaced that the synthetic rubber or rubber snubbing ring 10, seated on 9, will contact flange 7 at about the point where 7 merges into cover 5. The decreasing diameter of 7 pinches 10 between 8 and 7 in any upward movement of the dynamotor and cradle relative to base 6 and cover 5. By the arrangement hereabove set forth the blocks 3 provide adequate compression shock absorbing elements in movements of the cradle 1 toward the plates 4 while the ring 10 provides an adequate compression shock absorbing element in movements of the connection 8-9 toward the flange 7 of base cover 5. In effect, there is a complete cushion between the dynamotor and its base or support, capable of completely absorbing all shocks and vibrations between them.

These same elements 3 and 10 also provide complete electrical insulation between the parts.

The material preferred for the compression members 3 and member 10 is synthetic rubber. By a series of severe tests, it has been satisfactorily proven that in assembly such as here disclosed, synthetic rubber is efficient and will give the desired results whereas various other cushioning media are not so efficient or satisfactory.

It is thought that the construction, operation and use of the invention will be clear from the preceding detailed description.

Having thus disclosed my invention, what I claim and desire to protect by Letters Patent is:

1. An anti-vibration mounting of the character described comprising a base provided with an opening surrounded by a flange, a cradle adapted to receive and support a machine and provided with a centrally disposed downwardly directed tubular member adapted to be extended through said base opening and provided with a flange complementary to said base opening flange, compression anti-vibration members interposed between said cradle and said base and an anti-vibration member interposed between said flanges.

2. An anti-vibration mounting of the character described comprising a base provided with an opening surrounded by a flange, a cradle adapted to receive and support a machine and

provided with a centrally disposed downwardly directed tubular member adapted to be extended through said base opening and provided with a flange complementary to said base opening flange, compression anti-vibration members interposed between said cradle and said base and an anti-vibration member interposed between said flanges and positioned to be wedged between said flanges by relative approaching movement of said flanges.

3. In combination in an anti-vibration mounting of the character described, a base member provided with an opening therethrough surrounded by an inwardly and upwardly directed flange, a cradle disposed on said base and provided with a downwardly extending tubular member adapted to be passed through said opening and provided with a flange complementary to the flange about said opening, and an anti-vibration member confined between said flanges.

4. In combination in an anti-vibration mounting of the character described, a base member provided with an opening therethrough surrounded by an inwardly and upwardly curved flange, a cradle disposed on said base and provided with a downwardly extending tubular member adapted to be passed through said opening and provided with a downwardly and outwardly curved flange approximately complemen-

tary to the aforesaid flange, and an anti-vibration member of greater diameter than the opening through said base and confined between said flanges.

5. An anti-vibration mounting of the character described comprising a base provided with an opening therethrough surrounded by an upwardly and inwardly directed flange, a support provided with a tubular member extending through said opening and provided with a downwardly and outwardly directed flange substantially complementary to and spaced from the first mentioned flange and an anti-vibration member interposed between said flanges and positioned to be wedged between said flanges by relative approaching movement of said flanges.

6. An anti-vibration mounting of the character described comprising a base provided with an opening therethrough surrounded by an upwardly and inwardly directed flange, a support provided with a tubular member extending through said opening and provided with a downwardly and outwardly directed flange substantially complementary to and spaced from the first mentioned flange and a rubber ring interposed between said flanges and positioned to be wedged between said flanges by relative approaching movement of said flanges.
